(57) **CLAIM**

The ornamental design for a bicycle trailer, as shown.

DESCRIPTION

FIG. 1 is a right side isometric view of a bicycle trailer of the present invention, showing one embodiment of my new design;

FIG. 2 is a front elevation view of the embodiment of FIG. 1; FIG. 3 is a back elevation view thereof;

FIG. 4 is a right side elevation view thereof;

FIG. 5 is a left side elevation view thereof;

FIG. 6 is a top plan view thereof; and

FIG. 7 is a bottom plan view thereof.

FIG. 8 is a right side isometric view of a bicycle trailer of the present invention, showing another embodiment of my new design;

FIG. 9 is a front elevation view of the embodiment of FIG. 8; FIG. 10 is a back elevation view thereof;

FIG. 11 is a right side elevation view thereof;

FIG. 12 is a left side elevation view thereof;

FIG. 13 is a top plan view thereof; and,

FIG. 14 is a bottom plan view thereof.

In the drawings, the broken lines in the figures depict portions of the article that form no part of the claim.
